BOBBIE PIN BRACKET

Cora C. Albright, Akron, Colo.

Application July 1, 1937, Serial No. 151,536

2 Claims. (Cl. 211—60)

This invention relates to an improved holder or bracket for "bobbie" pins.

Much trouble is encountered in applying "bobbie" pins to the hair because of the necessity of holding the curl, to which the "bobbie" pin is to be applied, with one hand while applying. "Bobbie" pins are made of resilient metal and are shaped so that the gripping portions tightly engage against each other so that when the hair is placed between, it will not be accidentally disengaged. It is therefore very difficult, while using one hand to hold the curl, to open the "bobbie" pin so that it can be applied to the curl. The usual method employed is to open the pin with a finger nail or with the teeth, neither way being very satisfactory.

It is the object of this invention to produce a bracket especially adapted to hold a number of "bobbie" pins in an open position so that by gripping the pin between the thumb and first finger they can be removed from the bracket with the thumb and index finger holding the gripping portions in an open position ready to be applied to the hair.

This invention is especially adapted for use in cosmetology shops where "bobbie" pins are constantly being used and in addition to providing a practical means for holding the pins ready for use, it is also attractive in appearance and furnishes a place where the "bobbie" pins may be kept neatly and which will tend to prevent loss of the pins.

Other objects and advantages of the invention will hereafter become fully apparent from the following specification of which the drawing forms a part, and wherein:

Figure 1 is a top plan view of the invention,

Figure 2 is a side elevational view partly in section of the same, and

Figure 3 is a cross sectional view on the line 3—3 of Figure 2.

Referring more particularly to the drawing wherein like characters designate like or corresponding parts in the different views, 10 designates generally the bracket comprising a base 11, which may be of any desired shape, the neck 12 which extends upwardly from base 11; and the supporting members 13 extending outwardly from neck 12 and bent upwardly to form the portions 14 which are each provided with openings 15. A rod 16 having reduced ends 17 to engage 15 is mounted between the end portions 14. Rod 16 is covered with a casing 18 of rubber or the like.

The "bobbie" pins 19 comprise the loop 20 and corresponding gripping portions 21 formed of resilient metal. Loop 20 is shaped to cause the portions 21 to resiliently engage against each

other normally, so that when ends 21 engage casing 18 as seen in Figure 3 the pins 19 will be frictionally held in position.

Only one "bobbie" pin 19 has been shown but bracket 10 is obviously adapted to support as many as can be placed along the length of rod 16. In Figure 3 rod 16 is shown as being substantially rectangular in cross section to provide a better supporting surface for the portions 21, but it could also be made circular if desired. 10 Base 11, neck 12 and arms 13 merely illustrate the preferred form for mounting rod 16. Any other suitable supporting means could equally well be used. If desired casing 18 can be dispensed with, or other means employed to provide 15 a substantial gripping surface for portions 21.

From the foregoing it will be understood the "bobbie" pins 19 are opened and applied to bracket 10 as best seen in Figure 3. By gripping portions 21 between the thumb and index finger 20 pin 19 can be removed from rod 16 and held in an open position while being applied to the hair, thus greatly simplifying the effort required to apply the "bobbie" pins 19. It is a simple matter with both hands free to reload the rod 16 with 25 "bobbie" pins 19 so that much time can be saved since the reloading can be done when the user is not otherwise employed.

It is to be understood that only the preferred embodiment of the invention has been shown and described, the right being reserved to make such changes as do not depart from the spirit and scope of the invention as claimed.

I claim as my invention:

1. A "bobbie" pin bracket comprising a base 35 provided with outwardly and upwardly extending supporting arms, a rod mounted between said supporting arms, and a casing enclosing and extending the length of the rod, said casing being adapted to be frictionally engaged by a plurality 40 of "bobbie" pins to be held thereby in an open position ready to be applied.

2. A portable "bobbie" pin holder comprising a base, a neck formed integral therewith and projecting upwardly therefrom, a yoke shaped 45 member secured to the upper end of said neck and comprising arms extending outwardly from said neck in opposite directions, said arms being turned upwardly adjacent their free ends and being provided with openings in their upturned 50 portions, a rod having its end mounted in said openings and disposed above the intermediate portion of said yoke shaped member, said rod being polygonal shaped in cross section and adapted to be engaged by the free ends of the 55 resilient arms of a plurality of "bobbie" pins to mount the pins in an open position ready for use.

CORA C. ALBRIGHT.
